MAGAZINE FOR AUTOMATIC FIREARMS

George Ironside, Hartford, Conn., assignor to
Colt's Patent Fire Arms Manufacturing Com-
pany, Hartford, Conn., a corporation of Con-
necticut

Application October 20, 1941, Serial No. 415,757

5 Claims. (Cl. 89—34)

This invention relates to magazines for automatic firearms.

More particularly, it relates to improvements in magazines for automatic firearms of the machine gun type, such as illustrated, for example, in U. S. Patent No. 1,293,021 to Browning.

One of the objects of the invention is to provide a magazine accommodating a maximum amount of cartridges in a minimum amount of space adjacent the firearm whereby the magazine and firearm may be readily utilized in places where useful space is at a premium.

Another object of the invention is to provide a holder for a magazine box which is of simplified construction yet efficient and sturdy. Also, the design is such that accidental removal of the magazine box is prevented while at the same time, the box may be quickly inserted in or removed from the supporting means provided therefor.

Other objects of the invention will become apparent from studying the following specification in conjunction with the drawing which forms an integral part thereof.

The accompanying drawing shows the embodiment of the invention which is deemed preferable, but it will be understood that the drawing is intended for illustrative purposes only and is not to be construed as defining or limiting the scope of the invention, the claims forming a part of this specification being relied upon for that purpose.

In the drawing,

Fig. 1 is a perspective view of the improved magazine attached to a machine gun of the Browning type;

Fig. 2 is a side elevation of the frame for supporting the magazine;

Fig. 3 is an end elevation of said frame;

Fig. 4 is a side elevation of the magazine box; and

Fig. 5 is an end elevation of the magazine box with the lid of the box partly opened.

In mechanized war equipment such as tanks, armored cars, and other similar devices, the interior compartments in which the crews operate frequently contain only a minimum of available working space. Inasmuch as such mechanized devices generally carry machine guns and other articles of ordnance requiring magazines, it has been found impractical to now use magazines previously used in conjunction with machine guns and automatic firearms generally whereby it has become necessary to design new and improved types of magazines for such firearms. The instant

invention has been perfected to utilize a small amount of free space available immediately below the breech casing of a machine gun in a tank or other similar device.

In the drawing, as shown particularly in Fig. 1, a plurality of members are joined to form a frame 10 arranged to depend from the breech casing 12 of an automatic firearm, such as a Browning machine gun for example. The frame 10 is securely attached preferably to the side plates 14 of the breech casing by suitable bolts 16 having conventional nuts, as shown in Fig. 2. It is to be understood, of course, that such a frame may be secured to any other suitable part of an automatic firearm which may come within the spirit of this invention, and the illustrated attachment of the same to the breech casing is by way of example only.

In order that the feed of a cartridge belt from 20 the magazine may be as free as possible and no unusual twisting of the cartridge belt may take place, the frame 10 is preferably vertically aligned with the conventional feed channel 18 in the side of the breech casing of said firearm whereby the belt of cartridges is fed upward from the magazine to the feed channel 18 into which the belt is pulled or fed by the conventional belt feeding mechanism illustrated in said Browning Patent 1,293,021 which mechanism includes the belt engag- 30 gaging pawl 20.

The frame 10 is chiefly composed of two U-shaped bail members 22 which are adapted to have their ends directly attached to the side plates 14 of the breech casing by bolts 16 passing through 35 suitable apertures 24 in ears 26 formed on the ends of the bail members 22. The planes of the ears 26 are parallel to said side plates.

Projecting longitudinally from each side member of one of said bail members 22 is an extension 28. Each extension is adjacent the end of each of said side members and has an aperture there-through adapted to receive a shaft 30. Said shaft 30 is at present illustrated in the form of an elongated bolt passing between the extensions 28 and secured in the extensions by a suitable nut 32. Revolvably mounted for free rotation on the shaft is an elongated roller 34. The cartridge belt 36 partially passes around said roller for the purpose of reducing friction in 50 feeding the cartridge belt to the breech opening 18. In Fig. 1, the belt is illustrated as a conventional canvas belt but it is to be understood that any other suitable type of belt, such as an articulated link belt for example, will operate 55 in the magazine herein illustrated and described.

The lower, horizontal portions of the bail members 22 support a tray-like, quadrangular base member 38 affixed thereto, which base member is in the nature of a suspended platform adapted to receive the bottom face of a generally rectangular cartridge box 40 and hold the box in operative position. The transverse dimensions of the base member 38 are substantially the same as the bottom face of the box which engages and is supported by said base member. Base member 38 is formed with upstanding sides 42 on the edges of two sides and one end in order to properly align the cartridge box thereon. In effect, the opposite longest edge portions of said base member, in conjunction with their respective upstanding sides 42 may be considered as a pair of parallel guideways, extending transversely of the longitudinal axis of the gun, adapted to support the cartridge box. The upstanding side 42 on the end of the base member constitutes a stop to limit insertion of the box in the frame.

The cartridge box is adapted to be inserted into the frame through one open face or end and between the sides of the bails 22 onto base member 38 from the right-hand side, as viewed in Fig. 2. The above-mentioned open end or face of the frame is at the right-hand side of Fig. 2. To facilitate the insertion and removal of said box, the right-hand edge of base member 38 is shown to have an upstanding side 44 which is not as high as sides 42 but the side 44 is high enough to serve as a stop member to prevent accidental removal of the cartridge box from the frame as, for example, in cases where the gun may be tilted in a direction which would normally cause the box to fall from said frame if such a stop mechanism were not provided.

Horizontal bars 46 are secured to the side members of the bails 22, such as by welding or in any other suitable way, at a position between the ends of said side members of the bail, as shown in Figs. 1-3. Said horizontal bars extend beyond one of the bail members a sufficient distance to have the extending ends vertically aligned with the corresponding end of the base member, as shown in Fig. 2. Said extending ends of the horizontal bars have projections 48 turned inward toward each other, which projections serve as stop members for the box when the same is being inserted from the right-hand side as shown in Fig. 2. Thus, due to projections 48, the box may only be inserted into the frame far enough to be properly positioned, following which, the box will drop onto the base member 38 between the upstanding sides 42 and 44. The projections 48, in effect, supplement the aligning function of sides 42 and 44 and prevent moving the box clear through the frame when being inserted therein.

The side members of bails 22 are sufficiently long to afford adequate clearance for the box between the upper edge of the shortened side 44 and the underside of the breech casing whereby the box may be easily inserted in or removed from the frame.

The box 40 is preferably formed of sheet metal but may be formed of other suitable material. Said box is of generally rectangular shape having an upper, open face. The box is provided with a top or closure 50 having opposite, parallel, downwardly bent sides 54. The closure is pivoted at one of its ends to the upper edge of one end of the box by a suitable pin 52 passing through aligned openings in the sides 54 of the closure.

and the sides of the box. The pin is held in place by an outward extending, curved spring finger 53 mounted on the free end thereof as shown in Fig. 5. Such detachable locking means permits ready insertion and removal of the pin from the box and closure. The sides 54 each have an aperture 56 formed therein adapted to receive rounded projections 58 pressed outward from the sides of the box 40 and adapted to releasably hold the closure in closed position on the box.

As shown in Fig. 4, the closure 50 does not extend the full length of the box, the non-pivoted end thereof terminating short of the end of the box nearest thereto. Said non-pivoted end is curved upward, as shown at 60, to facilitate ready feeding of the belt from the magazine without undue binding.

As shown in Fig. 1, the upward curved end 60 of the box closure 50 is below and closely adjacent the roller 34 when the box is in operative position in the frame, whereby the curved surfaces of closure end 60 and roller 34 supplement each other to effect a smooth composite surface over which the belt 36 passes to the feed channel 18.

The upper part of the end of the box adjacent the curved portion 60 is cut out as shown at 62, see Fig. 5, which cut-out, in conjunction with the space provided by the shortened end of the closure, affords adequate space for the cartridge belt to pass from the box.

The design of the box and the frame is such that the box is inserted through the end of the frame opposite to that end from which withdrawal of the cartridge belt from the box and frame takes place whereby the pull of the cartridge belt on the box, when the belt is being fed to the breech, is against the permanent stop members of the frame comprising elements 48 and member 42 on the end of the base plate. Thus, the pull of the belt will not dislodge the box from the frame.

The magazine described in the foregoing is adapted to be used on a reversible feed type machine gun and to this end the design, dimensions, and arrangement of the component parts of the frame 10 are such that the frame may be reversed on the breech casing 12 by removing bolts 16 and rotating the frame in a horizontal plane 180 degrees, following which, the ears 26 may be bolted to the side plates 14 of the breech casing by the bolts 16 in the manner of attaching illustrated in Fig. 2. With the frame in the above-described reversed position on the breech casing, the cartridge box will still be inserted from the open end of the frame, which will then be disposed on the opposite side of the breech casing from the side now shown in Fig. 1. The cartridge belt will then be in position to be fed to the feed channel on the opposite side of the breech casing from the side now containing feed channel 18, and the function of all of the associated parts of the magazine will be the same as described in connection with the arrangement shown in Fig. 1.

While the base member 38 is shown to have a solid bottom, it is to be understood that a considerable portion of the central part of the base member 38 may be removed, thus leaving horizontal edge strips extending around the perimeter of the base member to which are joined the upstanding side members 42 and 44.

Primarily, both the roller 34 and the closure 50 of the box 40 are for purposes of facilitating

the feed of the cartridge belt to the breech opening. In using certain types of belts, either the roller or the closure or both may be found to be unnecessary. Thus, in such cases, the roller and/or the closure may be eliminated from the combined structure if such elimination is found desirable.

It will thus be seen that the present invention provides a very compact magazine arranged directly below the breech casing of a machine gun or other similar automatic firearm. The magazine has a box to hold an adequate number of cartridges, the number depending upon the size of the box. The cartridges may be directly fed to the feed channel in the breech casing of the gun without twisting the belt and in a manner which will reduce the possibility of jamming of the belt during feeding to a minimum. The present magazine is preferably designed to hold a belt containing about 100 rounds of ammunition but the design lends itself to holding belts of smaller or greater number of cartridges than this.

While the invention has been illustrated and described in its preferred embodiment and has included certain details, it should be understood that the invention is not to be limited to the precise details herein illustrated and described since the same may be carried out in other ways, falling within the scope of the invention as claimed.

What I claim is:

1. A magazine for an automatic firearm having a breech casing and a transverse feed channel, said magazine comprising a cartridge box adapted to hold a belt of cartridges, a bail member attachable to the breech casing of said firearm, a base member connected to the lower portion of said bail when in operative position on said breech casing and arranged to support said cartridge box, and an antifriction roller rotatably supported by said bail and adapted to be engaged by a cartridge feed belt in passing to the feed channel of said firearm.

2. A magazine for an automatic firearm having a breech casing and a feed channel extending transversely therethrough, said magazine comprising in combination, a pair of bails respectively arranged to be connected at their free ends to opposite sides of said breech casing and depend therefrom substantially parallelly to each other and below said feed channel, a base member supported by the lower portions of said bails and between the legs thereof, said base member extending between said bails and opposite ends thereof respectively projecting beyond said bails and the opposite sides of said breech casing, a cartridge box removably mounted on said base member and between the legs of each bail, stops projecting upward from said base member adjacent said opposite ends thereof and respectively arranged to engage opposite ends of and maintain said box in operative position on said base member and prevent accidental removal of said box from between said bails, and an additional stop carried by one of said bails above that one of said first-mentioned stops on said base which is nearest the entrance end of said feed channel, said additional stop being engageable with one side wall of said box, whereby a cartridge belt may be fed through said feed channel from said box and said additional stop will prevent the pull of the belt on said box from dislodging said box from its operative position

within said bails and between said first-mentioned stops.

3. A magazine for an automatic firearm having a breech casing and a feed channel extending transversely therethrough, said magazine comprising in combination, a pair of bails respectively arranged to be connected at their free ends to opposite sides of said breech casing and depend therefrom substantially parallelly to each other and below said feed channel, a base member supported by the lower portions of said bails and between the legs thereof, said base member extending between said bails and opposite ends thereof respectively projecting beyond said bails and the opposite sides of said breech casing, a cartridge box removably mounted on said base member and between the legs of each bail, stops projecting upward from said base member adjacent said opposite ends thereof and respectively arranged to engage opposite ends of and maintain said box in operative position on said base member and prevent accidental removal of said box from between said bails, the stop projecting from the end of said base member farthest from the entrance of the feed channel extending upward a shorter distance than the other stop to facilitate movement of the cartridge box thereover to and from operative position on said base member, and an additional stop carried by one of said bails and arranged above the highest stop on said base, said additional stop being engageable with one wall of said box, whereby a cartridge belt may be fed through said feed channel from said box and said additional stop will prevent the pull of the belt on said box from dislodging said box from its operative position within said bails and between said first-mentioned stops.

4. A magazine for an automatic firearm having a breech casing and a feed channel extending transversely therethrough, said magazine comprising in combination, a pair of bails respectively arranged to be connected at their free ends to opposite sides of said breech casing and depend therefrom substantially parallelly to each other and below said feed channel, a base member supported by the lower portions of said bails and between the legs thereof, said base member extending between said bails and opposite ends thereof respectively projecting beyond said bails and the opposite sides of said breech casing, a cartridge box removably mounted on said base member and between the legs of each bail, stops projecting upward from said base member adjacent said opposite ends thereof and respectively arranged to engage opposite ends of and maintain said box in operative position on said base member and prevent accidental removal of said box from between said bails, a pair of bars respectively carried by the legs of said bails on opposite sides of said cartridge box, said bars terminating at one end in an additional stop arranged above that one of said first-mentioned stops on said base which is nearest the entrance end of said feed channel and engageable with one side wall of said box, whereby a cartridge belt may be fed through said feed channel from said box and said additional stop will prevent the pull of the belt on said box from dislodging said box from its operative position within said bails and between said first-mentioned stops.

5. A magazine for an automatic firearm having a breech casing and a feed channel extending transversely therethrough, said magazine comprising in combination, a pair of bails respec-

tively arranged to be connected at their free ends to opposite sides of said breech casing and depend therefrom substantially parallelly to each other and below said feed channel, a base member supported by the lower portions of said bails and between the legs thereof, said base member extending between said bails and opposite ends thereof respectively projecting beyond said bails and the opposite sides of said breech casing, a cartridge box removably mounted on said base member and between the legs of each bail, stops projecting upward from said base member adjacent said opposite ends thereof and respectively arranged to engage opposite ends of and maintain said box in operative position on said base member and prevent accidental removal of said box from between said bails, the stop projecting from the end of said base member farthest from the entrance of the feed channel

extending upward a shorter distance than the other stop to facilitate movement of the cartridge box thereover to and from operative position on said base member, a pair of bars respectively carried by the legs of said bails on opposite sides of said cartridge box to further facilitate said movement of said cartridge box, said bars terminating at one end in an additional stop arranged above the highest stop on said base, said additional stop being engageable with one side wall of said box, whereby a cartridge belt may be fed through said feed channel from said box and said additional stop will prevent the pull of the belt on said box from dislodging said box from its operative position within said bails and between said first-mentioned stops.

GEORGE IRONSIDE.
